UNITED STATES PATENT OFFICE.

OTTO KAMPFE, OF BELLMORE, NEW YORK, ASSIGNOR OF ONE-HALF TO HENRY C. WALKER, OF NEW YORK, N. Y.

BOTTLE CAP.

1,423,431.

Specification of Letters Patent. Patented July 18, 1922.

Application filed July 31, 1920. Serial No. 400,473.

To all whom it may concern:

Be it known that I, OTTO KAMPFE, a citizen of the United States, residing at Bellmore, in the county of Nassau and State of New York, have invented an Improvement 5 in Bottle Caps, of which the following is a specification.

This invention relates to a bottle cap and more particularly to that type of bottle cap shown and described in my copending application, Serial No. 368,877, filed March 26, 1920, in which the parts comprising the bottle cap are made entirely of metal and are caused to inter-engage with one another 10 and to engage with the mouth of a bottle in the operation of applying the cap to the bottle to seal the same. The bottle cap made in accordance with the present invention preferably comprises a retainer member 15 adapted to engage the neck of a bottle and a closure member adapted to engage the mouth of a bottle to seal the same and preferably made of a non-corrosive material so that irrespective of the contents of the bot- 20 tle there can be no chemical action between the cap or any part thereof and the contents of the bottle to contaminate the contents and to destroy the cap and the seal by which the cap closes the bottle. The parts 25 of the cap made in accordance with this invention, like those described in the application aforesaid, are so constructed that it is also possible to employ therewith a label for advertising purposes as well, if desired, to 30 35 act as an auxiliary seal or indicating seal to make it possible to determine by inspection whether the bottle as originally closed and sealed by the improved cap has been opened and any of the original contents re- 40 moved therefrom or other material substituted for the original contents of the bottle, and the bottle cap made in accordance with this invention will be hereinafter more particularly described in conjunction with the 45 accompanying drawings.

In the drawing:

Fig. 1 is a plan view of the closure member forming a part of the bottle cap made in accordance with my present invention.

Fig. 2 is a plan of the closure member.

Fig. 3 is an elevation and partial sec-

tion showing the neck of the bottle with my improved cap applied thereto.

Fig. 4 is an enlarged transverse cross section illustrating the use of the label em- 55 ployed in conjunction with the improved bottle cap structure.

Fig. 5 is a plan of a label which may be employed in conjunction with the bottle cap, and 60

Fig. 6 is an enlarged plan view of the closure member, after the same has been shaped in the bottling operation.

Referring to the drawing, it will be seen that in carrying out this invention the bottle 65 cap made in accordance therewith comprises a retainer member and a closure member. The retainer member preferably includes an annular body portion 10 having a peripheral flange 11 in which there are 70 corrugations 12 adapted to fit over and engage the rib on the neck of a bottle adjacent the mouth thereof. The annular body 10 of the retainer member also includes the interior flange 13 which preferably extends 75 downwardly or in the same direction as the flange 11 and its edge is provided with series of notches 14 providing a corresponding number of teeth 15 therein.

Associated with the retainer member, I 80 employ a closure member. As illustrated in the drawing there is preferably a disk indicated at 16 and having a peripheral flange 17 made of any non-corrosive metal or other similar material. 85

In the use of the improved bottle cap the closure member with the peripheral flange is inserted in the retainer member and the parts are so connected that when so inserted there is sufficient frictional contact between 90 the parts to maintain the same in this associated relationship for the bottle capping operation. These parts then so associated are placed over the mouth of a bottle by any suitable means. For instance the bot- 95 tle is indicated at 18 and the bottle mouth at 19 while the rib adjacent the mouth of the bottle is indicated at 20. With these parts so associated the bottle capping apparatus forces the parts together and the 100 same against the neck of the bottle as clearly indicated in Fig. 3 so that the external flange

of the retainer member engages the rib 20 on the neck of the bottle and the teeth 15 and a portion of the internal flange 13 are depressed against the adjacent surface of the 5 closure member to force the same inwardly into close contact with the mouth of the bottle, while the peripheral flange 17 of the closure member is turned over beneath the body portion of the retainer member as 10 clearly indicated in Figs. 3 and 4 not only to unite the parts of the cap in a substantially inseparable relationship, but also to complete the capping operation by completing 15 the sealing of the bottle by the closure member.

It is also to be observed that in this bottle capping operation the flange 17 of the closure member first coming into contact with the inner surface of the circular portion 20 of the retainer member and doing so at substantially the same time that the teeth 15 in the periphery of the inturned flange of the retainer member contact with the closure member and acts as a cushion to prevent 25 any undue pressure being brought to bear or to be localized at the mouth of the bottle and at the same time permitting the capping tool to force the central portion of the closure member into the mouth of the 30 bottle by permitting portions of the outer parts of the closure member to slide inwardly along the surface of the mouth of the bottle before the flange becomes completely turned over, as hereinbefore 35 described and shown in the drawing, to assist in the sealing of the bottle by the parts of the cap.

Also as shown in the drawing, I may employ a label for advertising or other purposes, this label being indicated at 21 and having a central portion 22 which is preferably circular and adapted to be fitted between the retainer and closure members of the 40 cap before the same are permanently united in order that the upper portion of the face may be visible through the opening in the retainer member and may bear a suitable advertisement which is thus readily discernible. This label may be merely a disk fitting 45 between the parts of the bottle cap, or as indicated in Fig. 5 may have oppositely disposed ends or extensions 23, 24 adapted to extend down along side of and be secured to the neck of the bottle. This label, as will be 50 understood and as hereinbefore intimated may also serve the purpose of an indicator to show whether the seal of the bottle cap has been broken. This may be accomplished by providing the label on its inner surface 55 with one or more threads or strings indicated at 25 which extend across the central portion thereof and sufficiently far beyond the same to reach below the edge of the corrugated flange of the retainer member so that 60 the cap as originally placed on the mouth 65

of the bottle cannot be removed without destroying these threads or strings. Of course the extent to which the ends of the label are carried or the length of the indicator strings or cord are dependent upon the circumstances and conditions with which the same are employed, the label if necessary extending all the way to the bottom of the bottle, and for the strings or threads, suitable straps may be employed, of such a nature that they may be used in removing the cap from the bottle.

I claim as my invention:

1. A bottle cap comprising an annular retainer member having an external flange adapted to engage the neck of a bottle and an inwardly extending internal flange, and a closure member having a peripheral flange, the said closure member and its peripheral flange being adapted to be engaged in the sealing operation by the said inwardly extending internal flange of the retainer member to turn over the peripheral flange of the closure member causing the same to engage a portion of the internal flange of the retainer member, while the periphery of the internal flange of the retainer member forces a portion of the closure member into the neck of the bottle to effectually seal the same.

2. A bottle cap comprising an annular retainer member having an external flange adapted to engage the neck of a bottle and an inwardly extending flange, in the edge of which there are spaced teeth, and a closure member having a peripheral flange adapted in the capping operation to be secured to the retainer member by having its peripheral flange overturned within the same and to be engaged by the teeth at the edge of the inwardly extending flange of the retainer member and depressed thereby to engage the mouth of a bottle to seal the same.

3. A bottle cap comprising an annular retainer member having an external flange adapted to engage the neck of a bottle, a closure member adapted to be connected to the retainer member in the sealing operation, a label intermediate of the closure member and the retainer member so that in the capping operation the label is maintained between the retainer and closure members and the closure member is depressed by the retainer member to engage the mouth of a bottle to seal the same, and means associated with the label and extending beyond the external flange of the retainer member to indicate whether the cap as originally applied to the bottle has been removed and the original seal broken.

4. A bottle cap comprising an annular retainer member having an external flange adapted to engage the neck of a bottle, and an inwardly internal flange, and a non-corrosive metallic closure member having

a peripheral flange, the said closure member and its peripheral flange being adapted to be engaged by and connected with the said inwardly extending internal flange 5 of the retainer member in the sealing operation to turn over the peripheral flange of the closure member causing the same to engage a portion of the internal

flange of the retainer member, the internal flange of the retainer member causing a portion of the closure member to be forced into and directly against the neck and mouth of the bottle to seal the same. 10

Signed by me this 20th day of July, 1920.

OTTO KAMPFE.
